UNITED STATES PATENT OFFICE.

CARL Z. ALEXANDER AND EARL S. ALEXANDER, OF NEWARK, NEW JERSEY.

BOILER.

Application filed August 11, 1921. Serial No. 491,644.

To all whom it may concern:

Be it known that we, CARL Z. ALEXANDER and EARL S. ALEXANDER, citizens of the United States, and residents of Newark, 5 county of Essex, and State of New Jersey, have invented certain new and useful Improvements in Boilers, of which the following is a specification, taken in connection with the accompanying drawing, which 10 forms part of the same.

This invention relates especially to boilers for steam heating, etc., of the general type covered by the Alexander Patent No. 1,240,804 of September 25, 1917, and in 15 which one or more geyser tubes may be cast integral with or formed within the fire box section or fire pot water jacket so as to be more or less within the fire box. In the case of cast iron or cast steel fire box 20 sections of water jacket construction, three to five or so water legs or geyser tube members may be cast integral with the fire box so as to more or less bridge across its upper portion, and these bent or curved water 25 legs may advantageously be carried down a considerable distance below the normal or cold water level in the boiler or be otherwise connected to the water sections of the boiler, so that under firing conditions water under 30 considerable head is supplied to these water legs to be fed up through the connected geyser device by the action of the steam produced within the water. In this way any suitable steam chambers arranged 35 adjacent to or above the fire box may have water automatically supplied to their heating surfaces so as to be evaporated under efficient conditions; and these steam chambers preferably have ribs or projections to 40 feed the water over them in thin sheets or streams during its evaporation, the remaining water being returned to the water jacket or other part of the boiler circulation. Furthermore under extreme firing conditions 45 when the water jacket is sufficiently heated so that large volumes of steam are generated therein, this water can be carried up through supplemental water supply connections or tubes, so that further supplies of water are 50 furnished to the steam chamber heating surfaces under these conditions when they are needed.

In the accompanying drawing showing in a somewhat diagrammatic way illustrative embodiments of the invention. 55

Fig. 1 is a vertical section taken through the boiler along the line 1—1 of Fig. 3.

Fig. 2 is a corresponding section showing another geyser device arrangement.

Fig. 3 is a horizontal section taken substantially along the line 3—3 of Fig. 1; and

Fig. 4 is a corresponding section along the line 4—4 of Fig. 1.

The boiler may comprise any suitable fire box section such as the water jacket fire pot 65 1 of cast iron or other suitable material, which may be mounted on the base or ash pit section 3 having the usual ash door 4 below the grate on which the coal or other fire 5 may be made. This fire box may of 70 course, have a firing door such as 6 indicated in dotted lines, and other draft and cleaning doors and openings may of course be provided as desired. The geyser tube device may comprise the bent or depending water 75 legs 15 and the geyser chamber or junction box 16, connecting the different legs of which three to five more or less may be provided preferably of integral cast-in construction connected to the fire box water jacket. 80 In this way the water legs bridge or extend across the upper part of the fire box and have their inlet portions arranged at least considerably below the normal water level 85 31 in this water jacket, so that under firing conditions water under considerable head is supplied to the geyser device in which it is highly heated and vaporized to a sufficient extent to raise the water to the supplemental heating surfaces above the water line. For 90 this purpose a geyser tube or connection 17 may be provided having an effective area of about an inch or so for small sized domestic boilers which enables the water to be raised effectively a foot and more above the normal water line in this construction. If desired however, the geyser chamber or junction box may be raised considerably above the position indicated and as shown in Fig. 2, the water legs 65 may be arched or bent 95 up to a considerable extent and preferably be given a somewhat flatter cross section, especially at their lower ends 64 where they merge or join with the inner surface 62 of

the water jacket 61. The inlet openings 63 for these water legs or geyser tubes are preferably considerably below the normal water line 61, so that water is forced into these 5 geyser tubes and vaporized therein to a sufficient extent to raise the water through the junction box 66 and a connected geyser tube or up-take 67 leading to the upper steam chambers or heating surfaces of the boiler. 10 With this arrangement the fire box area is not greatly decreased and these geyser tube devices are arranged in the upper part of the fire box where they receive the greatest heat when a fire is started, so that the automatic feeding of water to the upper heating 15 surfaces is prompt and effective although in many cases the Fig. 1 arrangement has proved entirely satisfactory under service conditions. 20 Any desired number of steam chambers such as 7, 49 may be arranged adjacent the fire box and the series of horizontal steam chambers directly above the fire box is convenient and effective for small sized units. 25 The upper steam chamber 7 may have a series of water guiding ribs or projections indicated in Fig. 3 as comprising the annular ribs 38 and radial ribs 56, so that in connection with the recesses or water passages 30 54 in the annular ribs a series of labyrinth channels are formed through which the water flows in shallow streams from the top 42 of the geyser tube between the smoke passages 43. The connecting nipples 34 join 35 this upper steam head with the one or more steam chambers below and the screw bushings 35 may be used for securing tight connection between these parts if desired. The water may thus pass down these connecting 40 nipples adjacent the periphery of the steam chambers and then flow inward over the somewhat conical lower surface 22 of the lower steam chamber which as indicated in Fig. 4 is provided with similar guiding ribs or projections 23, 57, so as to form elongated 45 or zigzag water channels to effect the more efficient evaporation of the water in thin films or streams. The arrows in Fig. 4 show the direction of the water flowing through 50 these labyrinth channels 46 before the unevaporated water falls into the depression or well 20 and passes out of the radial passage 18, 24 and through the pipe connections 28, 29, 30 to the lower part of the fire 55 box water jacket for instance.

Under operating conditions, the fire heats the inner surface of the fire box water jacket which may have the ribs or corrugations 14 to increase this heat absorbing action, and 60 steam is simultaneously generated in the geyser chamber and connecting tubes of the geyser device, so that the water is automatically raised and carried up to the one or more steam chambers above where it is evaporated quickly and efficiently and the steam 65 withdrawn through the steam lines such as 27, 47. Under forced firing the evaporation in the fire box water jacket often becomes sufficient to raise the normal water level 31, and carry further quantities of water up 70 through the nipples or connections 37 which may be screwed or forced into the upper end of the water jacket and into one of the steam chambers above. As indicated the upper end 36 of these supplemental water supply 75 connections may extend somewhat above the adjacent portions of the floor of this steam space or chamber 44; may also have an adjacent raised section as indicated in Fig. 3 in some cases, so that even if intermittent 80 supplies of water pass through this connection it tends to flow around the steam chamber so as to be evaporated thereon or on the heating surfaces of the steam chamber below after passing down through the connections 85 34. This action is quite desirable in such domestic or other steam boilers and if desired four to six such supplemental water supply connections may be provided which also allow the passage of steam through the 90 water jacket under low or moderate firing. In some cases it is advantageous also to have the lower parts of these connecting nipples threaded and to use the threaded bushings or nuts 60 thereon to force the two steam 95 chambers together in addition to the action of the bolts and nuts 10, 11 clamping together the flanges 8 and 9. As indicated the flue gases from the fire may pass around the lower steam chamber 49 which may have 100 recesses 48 for the nipple connections 37. The flue gases may then pass under the lower surface 52 of the upper steam chamber and through any desired number of smoke 105 passages 43. These two steam chambers 110 may also be connected as by the push nipple 40 which allows steam to pass between them when as is sometimes desirable, the head or spreader 42 is raised slightly above the top of this nipple. This type of boiler has 115 proved highly efficient in operation and its light weight is also another decided advantage growing out of the rapid circulation and advantages secured by the geyser device 120 of the type described.

This invention has been described in connection with a number of illustrative embodiments, forms, proportions, parts, arrangements, materials, constructions and methods of manufacture and use, to the details of which disclosure this invention is not of course to be limited, since what is claimed as new and what is desired to be secured by Letters Patent is set forth in the appended claims.

We claim—

1. A boiler comprising a substantially vertical cylindrical fire pot water jacket of cast metal having a cast-in geyser chamber and connecting water legs therefor bridg-

- ing the upper part of said fire pot, an upwardly extending geyser tube connected to said geyser chamber to receive water therefrom under firing conditions, upper and 5 lower substantially horizontal steam chambers arranged above said fire pot water jacket and having heating surfaces provided with tortuous channels to conduct water thereover in thin sheets or streams, said 10 geyser tube discharging adjacent the center of said upper steam chamber which is downwardly and outwardly inclined, water connections between the peripheries of said steam chambers and a water drip connection 15 between said lower steam chamber and said water jacket, and supplemental water supply connections between the upper part of said water jacket and the periphery of said upper steam chamber to automatically supply 20 additional water thereto under extreme firing conditions.
2. A boiler comprising a substantially vertical fire pot water jacket of cast metal having a cast-in geyser chamber and connecting water legs therefor bridging the upper part of said fire pot, an upwardly extending geyser tube connected to said geyser chamber to receive water therefrom under firing conditions, upper and lower substantially horizontal steam chambers arranged 25 above said fire pot water jacket, said geyser tube discharging adjacent the center of said upper steam chamber which is downwardly and outwardly inclined, water connections 30 between said steam chambers, and supplemental water supply connections between the upper part of said water jacket and the periphery of said upper steam chamber to automatically supply 35 additional water thereto under extreme firing conditions.
3. A boiler comprising a substantially vertical fire pot water jacket having a geyser chamber and connecting water legs therefor bridging the upper part of said fire pot, an upwardly extending geyser tube connected to said geyser chamber to receive water therefrom under firing conditions, upper and lower substantially horizontal steam chambers arranged above said fire pot water 45 jacket, said geyser tube discharging adjacent the center of said upper steam chamber which is downwardly and outwardly inclined, water connections between said steam chambers, supplemental water supply 50 connections between the upper part of said water jacket and said steam chambers to automatically supply additional water thereto under extreme firing conditions.
4. A boiler comprising a substantially vertical cylindrical fire box water jacket section of cast metal having a cast-in geyser chamber and connecting water legs therefor bridging the upper part of the fire box, an upwardly extending geyser tube connected 55 to said geyser device to receive water therefrom under firing conditions, steam chambers arranged above said fire box section and having heating surfaces above the normal water level and provided with means to conduct thereover in thin sheets or streams the 60 water from said geyser tube, and water and connections between said steam chambers.
5. A boiler comprising a substantially vertical fire box water jacket section of cast metal having a cast-in geyser device and depending water supply connections therefor bridging the upper part of the fire box, an upwardly extending tube connected to said geyser device to receive water therefrom under firing conditions, a steam chamber arranged above said fire box section and having heating surfaces above the normal water level and provided with means to conduct thereover in thin sheets or streams the 65 water from said tube.
6. A boiler comprising a fire box water jacket section having a geyser device and depending water supply connections therefor bridging the upper part of the fire box and integrally connected thereto, an upwardly extending geyser tube connected to said geyser device to receive water therefrom under firing conditions and a connected steam chamber arranged considerably 70 above the normal water level of the boiler and having heating surfaces to receive the stream of water automatically discharged from said geyser device under firing conditions.
7. A boiler comprising a fire box section of cast metal having a cast-in geyser device comprising a connected depending bent water leg therefor bridging the upper part of the fire box, a geyser tube connected to said geyser device to receive water therefrom under firing conditions and a steam chamber arranged above said fire box section, and having heating surfaces provided with means to conduct water thereover in thin sheets or streams, said geyser tube communicating with said steam chamber.
8. A boiler comprising a fire box section of cast metal having a geyser device connected to a water space of the boiler and extending into the upper part of the fire box, a geyser tube connected to said geyser device to receive water therefrom under firing conditions, and a steam chamber arranged above said fire box section and having heating surfaces provided with means to conduct water thereover in thin sheets or streams, said geyser tube communicating with said steam chamber to supply water thereto.
9. A boiler comprising a fire box water jacket section having a geyser device and depending water supply connections therefor bridging the upper part of the fire box, an upwardly extending geyser tube connected to said geyser device to receive water therefrom under firing conditions and a con-

nected steam chamber arranged above the normal water level of the boiler and having heating surfaces to receive the water automatically discharged from said geyser device under firing conditions.

10. A boiler comprising a substantially vertical fire box water jacket having a geyser chamber and connecting water legs therefor adjacent the upper part of the fire box, 10 an upwardly extending geyser tube connected to said geyser chamber to receive water therefrom under firing conditions, upper and lower steam chambers arranged above said fire box water jacket and having 15 heating surfaces provided with tortuous channels to conduct water thereover in thin sheets or streams, said geyser tube discharging adjacent the center of said upper steam chamber which is downwardly and outwardly inclined, water connections between the peripheries of said chambers and a water drip connection between said lower steam chamber and said water jacket, and supplemental water supply connections between 20 the upper part of said water jacket and the periphery of said upper steam chamber to supply additional water thereto under extreme firing conditions.

11. A boiler comprising a fire box water jacket having a geyser device adjacent the upper part of the fire box, an upwardly extending tube connected to said geyser device to receive water therefrom under firing conditions, steam chambers arranged above said fire box water jacket and having heating surfaces to conduct water thereover in thin sheets or streams, said tube discharging adjacent the center of said steam chamber which is downwardly and outwardly inclined, water connections between the peripheries of said steam chambers, and supplemental water supply connections between the upper part of said water jacket and the periphery of said upper steam chamber to supply additional water thereto under extreme firing conditions.

12. A boiler comprising a fire box water jacket having a geyser device adjacent the upper part of the fire box, an upwardly extending tube connected to said geyser device to receive water therefrom under firing con-

ditions, steam chambers arranged above said fire box water jacket, water connections between said steam chambers, and supplemental water supply connections between the upper part of said water jacket and said steam chambers to supply additional water thereto under extreme firing conditions.

13. A boiler comprising a water jacket fire box section having a geyser device adjacent the fire box, a geyser tube connected to said geyser device to receive water therefrom under firing conditions, a steam chamber arranged above said fire box section and having heating surfaces above the normal water level, said geyser tube communicating with said steam chamber to supply water thereto, and supplemental water supply connections between the upper part of the water jacket of said fire box section and said steam chamber to supply additional water thereto under extreme firing conditions.

14. A boiler comprising a water jacket fire box section having a geyser device adjacent the fire box, a tube connected to said geyser device to receive water therefrom under firing conditions, a steam chamber arranged adjacent said fire box section and having heating surfaces above the normal water level, said tube communicating with said steam chamber to supply water thereto, and supplemental water supply connections between the water jacket of said fire box section and said steam chamber to supply additional water thereto under extreme firing conditions.

15. A boiler comprising a fire box section having a geyser device adjacent the fire box, a steam chamber arranged adjacent said fire box section and having heating surfaces above the normal water level, said geyser device communicating with said steam chamber to supply water thereto, and supplemental automatic water feeding devices extending adjacent said fire box section and communicating with said steam chamber to supply additional water thereto under extreme firing conditions.
